UNITED STATES PATENT OFFICE.

MAHLON E. LAYNE AND SAMUEL N. HALL, OF LOS ANGELES, CALIFORNIA; SAID HALL
ASSIGNOR TO SAID LAYNE.

WELL MECHANISM.

Application filed March 6, 1922. Serial No. 541,289.

To all whom it may concern:

Be it known that we, MAHLON E. LAYNE and SAMUEL N. HALL, both citizens of the United States, residing at Los Angeles, in the county of Los Angeles and State of California, have invented certain new and useful Improvements in Well Mechanism, of which the following is a specification.

The invention relates to well mechanism and particularly to pump mechanism involving the use of a pump placed in or adjacent the water of the well and transmission and discharge mechanism extending to the surface of the ground and comprising a vertical operating shaft surrounded by a protecting and bearing supporting casing, and a discharge casing surrounding the shaft casing.

It often happens that the well bore is not straight and as a result, the discharge casing is correspondingly bent out of true. In such case, if the shaft casing is held concentric with the discharge casing by the usual spider or other bracing means, such shaft casing is bent out of true in correspondence with the shaft casing, thus causing the bearings in the shaft casing to bind the shaft and resulting in large power losses and undue wearing of the bearings.

In our application, Serial Number 408,941, filed September 8, 1920, we disclosed means for applying tension to the shaft casing for holding it straight, and self adjusting bracing means arranged at intervals along the length of the two casings and adapted to be applied after the casings were assembled, so that regardless of any lack of trueness in the discharge casing, the shaft casing might be held perfectly true and straight and braced in such position. The present invention is directed to a species of the broad invention disclosed in such prior application, and its object is to provide a very cheap and simple way of applying said broad invention, and one which may be more readily applied to our standard type of well equipment than the particular embodiment of the invention illustrated and described in the prior application.

In said prior application, the wedge bracing means were designed to be released after the casings were assembled by a vertical movement of the shaft casing, which casing was capable of such movement by

reason of the spring tension feature applied at the lower end of the shaft casing. In the present construction, the wedges are made releasable by a flexible means such as a cable, extending up between the two casings, so that no movement of the shaft casing is necessary in order to release the wedges, this being accomplished by pulling upward on the cable after the casings are assembled. This construction does not therefore require the use of the spring tension feature, and may be easily applied to our standard well construction. The spring tension feature of the prior application is one of value, and it may be desirable to use it in connection with the wedge releasing means of the present application, but in other cases, it may be advisable not to use the spring tension feature, in which the present release means is advisable because of its simplicity and ease of operation. For this reason the spring tension feature of the prior application is not illustrated in the present application, but it will be understood that it may be used, and further, that in the use of the present construction tension is actually applied to the shaft casing in the way hereinafter described to pull it straight before the bracing wedges are released, although no spring means are used. Certain embodiments of the invention are illustrated in the accompanying drawings wherein;

Figure 1 is an assembled sectional view of the upper part of a pump equipment embodying the invention. Fig. 1^a is a sectional view of the lower part of such equipment including the pump itself. Fig. 2 is an enlarged vertical section at one of the bracing devices between the discharge and shaft casings. Fig. 3 is a section on the lines III—III of Fig. 2, and Fig. 4 is an enlarged vertical section showing a modified form of bracing device.

Referring first to the general arrangement of Fig. 1 which illustrates an assembled pump embodying the invention hereinafter described, the principal parts are as follows: 1 is the pump casing of a single stage pump in which are mounted the impellers 2 secured to the drive shaft 3; 4 is the shaft casing carrying a series of spaced bearings 5; 6 is the discharge casing secured to the pump casing and extending to the surface of the ground and having the

lateral discharge outlet 7; 8 is a thrust bearing for supporting the weight of the shaft 3; and 9 is the belt pulley by means of which the drive shaft is operated.

5 In order to brace the shaft casing, and provide for the automatic positioning of such bracing means, the device shown in Figs. 2 and 3 is employed. Only three of these devices are shown in Fig. 1 and Fig. 10 1^a, but it will be understood that in the ordinary pump installation which may involve locating the pump anywhere from fifty feet to several hundred feet below the surface of the ground a number of these devices will be employed, and it will also be understood that the number of sections of shaft, shaft casing and discharge casing, as illustrated in Fig. 1, may be multiplied to meet conditions, drawings showing for 20 convenience of illustration, a minimum number of such sections.

As shown in Figs. 2 and 3, the bracing device comprises the ring member 10 secured to the coupling 11 and provided with 25 a series of vertical guideways 12 (Fig. 3) spaced at equal intervals around the ring. Mounted in these guideways 12 are the wedges 13. Fig. 2 shows these wedges in inoperative position being held in the 30 position shown by the cord or other flexible member 14 which passes through perforations 15 in the wedges. These wedges are secured in position as the casings are assembled, so that when the structure is completed and positioned in the 35 ground there is a plurality of wedging devices all held in inoperative position by the cords and spaced at suitable intervals along the length of the casing. In order to provide means for releasing the wedges and permitting them to drop to operative position a flexible member, preferably a small wire rope or cable 16 is employed. As the 40 sections are assembled and the wedges secured in position by means of the cords 14, such cords are secured to the cable 16 by means of the small ropes or wires 17. In order to release the wedges the upper end of the cable is grasped through the outlet 50 opening 7 and sufficient force is supplied to break the various cords 14 which support the wedges, thus permitting them to drop to operative position. In order to facilitate this breaking loose of the cords 14 55 slack is provided in the cable 16 between the successive cords 14 so that when force is applied to the cable the cords will be broken one after the other instead of all together.

To assist gravity in positioning the 60 wedges after the cords are broken, small springs 18 may be employed if desired, the upper ends being secured to hooks 19 in the bottoms of the wedges and to hooks 20 screwed into the shaft casing. In order to 65 prevent any upward movement of the

wedges when force is applied to the cable 16 to break the cords 14, small stud bolts 21 may be screwed into the shaft casing just above the upper ends of the wedges. To apply tension to the shaft casing 4 to insure that it may be pulled straight before the wedges are released, the coupling 22 (Fig. 1) is screwed up tightly, the shaft casing 6 acting as a strut opposing this tension. In this way the shaft casing may be 70 made straight even though the discharge casing is somewhat out of true incident to the well bore not being entirely straight. When the cable 16 is pulled upward breaking the cords 14, the wedges all drop to wedging position in the rings 10, each wedge sliding down until it acts as a bracing means. These bracing means securely hold the shaft casing in true position thus avoiding the imposition of any binding strain on 75 the shaft bearings in the casing.

It will be seen that this species of bracing means may be readily applied to a standard type of well construction and that the devices may be applied easily and conveniently during the usual assembling operation. Also that the cable and securing cords constitute an effective and cheap means for securing the positioning of the wedges after the parts are assembled and independent of any movement of the shaft casing such as that required in the form of invention illustrated in our prior application heretofore referred to. A wide variety 80 of wedge constructions, releasable holding means, and longitudinally extending holding means might be employed in place of the ones shown without departing from the spirit of the invention which contemplates 85 any and all means for releasing the wedges independent of any movement of the shaft casing.

It will be apparent that the invention is not limited to the use of wedges as bracing means although wedges constitute the preferred bracing means. For instance, in the construction of Fig. 4, the bracing is accomplished by means of a series of preferably three cylinders A, spaced around the circumference of the discharge casing and provided with the pistons 24 carrying the rods 25. The ends of these rods are pivotally connected to a ring 26 mounted upon the shaft casing. The rear ends of these rods have a ball and socket connection 27 with the pistons so that the parts may adjust themselves in case the axis of the cylinder does not come exactly in line with the center line of the ring 26. Pressure is applied behind the pistons by means of a pipe 28 connected with a source of fluid pressure by means of the pipe 29 running upward to the surface of the ground. A check valve 30 is located in a connection 31 so that after the fluid pressure has been 100 105 110 115 120 125

applied any backward movement of the piston is prevented. The fluid used is preferably oil, and the pressure is applied after the casings have been positioned in the well. It will be noted that this method of applying the bracing device is like the first form of device illustrated in that the braces may be adjusted independent of any movement of the shaft casing, although not so desirable as the preferred construction because of the complication and expense involved.

What we claim is:

1. In combination in a well mechanism, 15 a pump, a discharge casing extending upwardly from the pump, a power transmission shaft extending upward from the pump, a shaft casing surrounding the shaft and provided with a series of spaced bearings for the shaft, a series of self-adjusting bracing means arranged at intervals along the length of the shaft casing between such casing and the discharge casing, and adapted when in operative position to hold 20 the shaft casing rigidly against lateral movement with respect to the discharge casing, means for holding said devices in inoperative position during the assembling of the casings, and means independent of the 25 shaft casing for releasing said bracing means one after the other after the casings are assembled.

2. In combination in a well mechanism, 30 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft casing between such casing and the discharge casing, means for holding the wedges in inoperative position during the assembling of the casings, and releasing 35 means for the wedge holding means extending up between the casings to the upper end thereof whereby the wedges may be released one after the other and move to operative position after the casings are assembled.

3. In combination in a well mechanism, 40 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft casing between such casing and the discharge casing, means for holding the wedges in inoperative position during the assembling of the casings, and releasing 45 means for the wedge holding means extending up between the casings to the upper end thereof whereby the wedges may be released one after the other and move to operative position after the casings are assembled.

4. In combination in a well mechanism, 45 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft casing between such casing and the discharge casing, means for holding the wedges in inoperative position during the assembling of the casings, and a flexible member arranged to release the wedge holding means one after the other extending up between the casings to the upper end 50 thereof whereby the wedges may be released and move to operative position after the casings are assembled.

5. In combination in a well mechanism, 55 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft casing between such casing and the discharge casing, means for holding the wedges in inoperative position during the assembling of the casings, and a flexible member arranged to release the wedge holding means one after the other extending up between the casings to the upper end 60 thereof whereby the wedges may be released and move to operative position after the casings are assembled.

6. In combination in a well mechanism, 65 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft casing between such casing and the discharge casing, means for releasably securing the wedges to the shaft casing above their positions of use, and a flexible means 70 extending up between the casings to the upper end thereof and secured to the wedge securing means for releasing such means and permitting the wedges to move to wedging position after the casings are assembled, 75 such flexible means having slack between the successive securing means so that the wedges may be released one after the other.

7. In combination in a well mechanism, 80 a pump, a discharge casing extending upwardly from the pump, a power transmission shaft extending upward from the pump, a shaft casing surrounding the shaft and provided with a series of spaced bearings for the shaft, a series of wedges arranged at intervals along the length of the shaft between such casing and the discharge casing, flexible securing means for fastening the wedges releasably to the shaft casing above their positions of use, and a flexible means 85 extending up between the casings to the upper end thereof and fastened to said securing means for releasing such means and permitting the wedges to move to wedging position after the casings are assembled.
